UNITED STATES PATENT OFFICE.

ABILIO MARIA DA SILVA GREAVES, OF CAMBRIDGE, MASSACHUSETTS.

THE THERMO-ELECTRIC FIRE-ALARM SYSTEM.

1,251,366.

Specification of Letters Patent. Patented Dec. 25, 1917.

Application filed June 11, 1914. Serial No. 244,479.

To all whom it may concern:

Be it known that I, ABILIO MARIA DA SILVA GREAVES, a citizen of the Republic of Portugal, residing at Cambridge, in the county of Middlesex and State of Massachusetts, have invented certain new and useful Improvements in Thermo-Electric Fire-Alarm Systems, of which the following is a specification.

10 This invention relates to improvements in thermo-electric fire alarm systems and has to do more particularly with a novel form of thermostatic circuit closer whereby an appreciable increase of efficiency and a general simplification of parts may be obtained.

15 It is a special object of this invention to provide a column of mercury or like circuit closing fluid medium with an expansion chamber or chambers located above the normal level of the mercury, at normal temperature, and one or more terminals extending into said chamber or chambers in such a manner as to be enveloped by the expanding mercury as the same enters the chamber or 20 chambers so as to effectively close circuit and energize the alarm.

25 A further object is to adjustably mount the terminals so that they may be projected into the expansion chambers to a greater or less extent thereby varying the time at which the alarm is energized but always insuring an effective electrical contact with the mercury irrespective of the position of the terminals in said chambers.

30 35 A further and every special object of the invention is to increase the cross section of the expansion chamber or chambers from their lower toward their upper portions so that adjustment of the terminals upwardly will retard energization of the alarm while a reverse adjustment of the terminals downwardly will advance such energization.

40 Other objects and features of the invention will be more fully described in connection with the accompanying drawing and will be more particularly pointed out and ascertained in and by the appended claims.

In the drawing:—

Figure 1 is a view, partly diagrammatic, illustrating the preferred form of my invention electrically connected up with an alarm device.

Fig. 2 is a vertical sectional view of the preferred construction of circuit closer.

Like characters of reference designate

similar parts throughout the different figures of the drawing.

Referring more particularly to Fig. 1, an alarm system is shown including a mercury circuit closer, indicated as a whole at 1 and 50 having terminals 2 and 3 connected with conductors 4 and 5, respectively, of an alarm circuit. Conductor 4 is connected with one pole of a source of current, indicated at 6, and the other pole of said source of current 55 is connected by a conductor 7 with an alarm device which may be in the form of an electric bell 8. The connection of conductor 7 with the alarm device 8 is indicated at 9, and conductor 5 is connected with the alarm 70 device indicated at 10.

In view of the fact that the device of my invention relates to the circuit closer, the latter is only shown in one figure connected up with the circuit as the application to the 75 circuit of other forms of my invention will be clearly understood to those skilled in the art.

Referring more particularly to Fig. 2, which illustrates the preferred construction, 80 11 designates a suitable base upon which the tube 12 may be secured by means such as a clip 13. The tube 12 is provided with a reduced bore 14 which terminates at its lower end in a bulb 15 and which is of sufficient 85 length to provide for considerable expansion of the mercury in the bore 14 above points of normal temperature. The tube 12 will preferably be of glass and above the elevations 90 of normal temperature to which the mercury may rise, the tube 12 is provided with an enlargement 16 which converges, as indicated at 17, toward the normal cross section of the bore 14. The enlargement 16 provides for an expansion of the mercury when 95 it enters the chamber thereby reducing the rapidity of its ascent from the time that the expanding mercury reaches the diverging wall portions 17 of the expansion chamber, 100 for a purpose which will presently appear. The tube 12 is provided with a downwardly converging partition 18 having a pointed end 19 which extends a sufficient distance 105 downwardly to approximately approach the normal cross section of the bore 14 but not sufficiently to actually enter the bore 14. The partition 18 serves to reduce the amount 110 of expansion in area of the chamber at the point of entrance of the ascending mercury therein. The partition 18 functions to di-

110

vide the chamber or enlargement 16 into two chambers 20 and the latter diverge to their greatest cross section, as indicated at 16, and then converge toward the partition 18, as indicated at 21. The convergence at 21 and the divergence of the partition 18 serves to reduce the area of the chambers 21 toward their upper portions and the tube 12 is provided with bores 22 which communicate with the chambers 20. The bores 22 are formed in a forked upper end of the tube 12, the fork portions being indicated at 23 and the bores 22 extending throughout the length of the fork portions 23. On the forked ends 23 I dispose caps 24 provided with threaded stems 25. Nuts 26 have threaded connection with the stems 25 so as to electrically connect conductors 4 and 5 with the fork terminals. The caps 24 may be threaded or otherwise adjustably mounted on the forked ends 23 so that they can be secured thereto in the extreme lower position shown in Fig. 2, or adjusted in relatively elevated positions with respect to 25 such extreme lower position.

I electrically connect with the conductor terminals on the forked ends, or in other words, with each, a circuit closing terminal wire 27 which extends downwardly through 30 the expansion chambers 20, and, in the adjustment shown in Fig. 2, approximately to the upper end of the bore 14.

In the adjustment shown, as soon as the temperature rises so that the expanding 35 mercury will ascend to the approach or beginning of the diverging wall 17, the contact or circuit closing terminals 27 will be electrically connected with each other through the mercury so as to close circuit 40 and energize the alarm device. Further ascent of the mercury in the chambers 20 will decrease as the ascending mercury rises, as to the rate of ascent, but an open area will be afforded so as to insure an effective electrical connection between the mercury and the circuit closing terminals 27 because of 45 the fact that the latter will be immersed in the former with the latter disposed in an area greatly exceeding in cross section the 50 area of the bore 14.

Now should it be desired to retard circuit closing actuation of the device, from the adjustment shown in Fig. 2, the caps 24 will be adjusted so that the ends of the 55 circuit closing terminals 27 will be disposed upwardly in the chambers 20 and thereby the retarding action due to increased area in the chambers 20 with respect to the bore 14, will delay the ascent of the mercury and 60 therefore the alarm device will not be energized until a relatively higher temperature is reached, such temperature having reference to an extreme or higher temperature which is considerably above the normal.

65 It is to be noted that the lower end por-

tions of the terminals 27 are permanently bowed, or curved longitudinally, so that the points thereof may be brought into very close relation immediately between the inverted apex of the partition 18 and the 70 opening of the vertical bore 14, and also that, in adjusting them vertically of the chamber, the free ends of the same will be moved into contact with respective inclined walls of the partition. Further vertical adjustment of the terminals 27, causes the free ends to slide up the inclined walls, with a resultant bowing outward of the intermediate portions thereof, which action provides for the jarring loose and discharge therefrom of any of the mercury such as would otherwise tend to accidentally close circuit the terminals, if allowed to remain thereon, and particularly so, when the ends of the latter are disposed in their lower position. 80

This adjustability permits of the device being set for operation at any extreme temperature.

In practice the tube is shielded by a metal guard (asbestos wire) to protect said tube 90 from direct flame, in order to maintain a maximum period of time for the alarm signal. The bulbs are so designed as to care for the expansion of the mercury up to the melting point of the glass, and the function 95 of the expansion chambers is to prevent breakage of the glass due to excessive temperature.

While a specific form of the invention has been shown it will be understood that the invention is not to be limited except for such limitations as the claim may import.

I claim:—

1. A thermostatic circuit closer comprising a mercury tube including a bore and an expansion chamber communicating with the upper end of the bore, a triangular shaped partition depending within said expansion chamber and having its apex terminating immediately above the bore of said tube, terminals depending within said expansion chamber at opposite sides of said partition and curving into close proximity with respect to the bore of said tube and to each other, and means for adjusting said terminals within said expansion chamber, the curved ends of said terminals engaging the inclined walls of said partition, during the adjusting movement, to free the same from such particles of the mercury adhering thereto.

2. A thermostatic circuit closer comprising a mercury tube including a bore and an expansion chamber communicating with the upper end of the bore, said chamber being of maximum area at the medial point and tapering to gradually diminishing areas toward the extremities thereof, a triangular shaped partition depending within said expansion chamber and having its apex ter-

minating immediately above the bore of said tube, extensions formed with said expansion chamber and having bores communicating with the latter at opposite sides of said partition, terminals supported within the bores of said extensions and depending within said expansion chamber, the lower ends of said terminals being curved into close proximity with respect to the bore of said tube 10 and to each other, and means for adjusting said terminals within said expansion chamber, the curved ends of said terminals engaging the inclined walls of said partition during the adjusting movement, to free the 15 same from such particles of the mercury adhering thereto.

3. A thermostatic circuit closer comprising a mercury tube including a bore, an expansion chamber formed at the upper end of said tube and communicating with said bore, extensions formed with said expansion chamber and having bores communicating with the latter, the walls of said expansion chamber curving outwardly from opposite 25 sides of the bore of said tube and upwardly to the bores of said extensions, a triangular shaped partition depending within said expansion chamber and having its oppositely inclined walls extending from the bores of said extensions to a point immediately above the bore of said tube, terminals supported within the bores of said extensions and projecting into said expansion chamber, the lower end portions of said terminals being permanently bowed and spaced from the opposed walls of said expansion chamber and said partition, and means for adjusting said terminals within said expansion chamber, the curved ends of said terminals engaging the inclined walls of said partition, during 30 the adjusting movement, to further bow the curved portions thereof, whereby to free the same from such particles of the mercury adhering thereto.

In testimony whereof I affix my signature 41 in presence of two witnesses.

ABILIO MARIA DA SILVA GReAVES.
